UNITED STATES PATENT OFFICE.

JAMES LAROCCA, OF CICERO, ILLINOIS, ASSIGNOR TO ELECTRO-MAGNETIC TOOL COMPANY, OF CICERO, ILLINOIS, A CORPORATION OF ILLINOIS.

IMPACTING TOOL.

Application filed August 23, 1924. Serial No. 733,750.

My invention is a mechanical movement finding useful employment in various ways, the mechanism of my invention being of particular service when employed in the 5 operating mechanism of an impacting tool.

The mechanism of my invention includes a rotatable carrier, a plunger carried thereby, mechanism for effecting intermittent turning movements of the carrier and for 10 shifting the plunger to alternative positions, and an abutment with which the plunger has escaping engagement when the carrier is turned to engage the plunger and abutment. This abutment may be the butt 15 or striking end of a drill or rivet set when the invention is embraced in an impacting tool. In the preferred embodiment of the invention an electric motor drives the carrier through the intermediation of gearings 20 which permits the rotation of the carrier to be arrested by the abutment, this gearing cooperating with the abutment to effect the withdrawal of the plunger from the position to which it is placed by a spring, the 25 spring in turn, serving to effect rapid movement of the carrier when the plunger escapes the abutment to move the plunger rapidly to normal position with respect to the carrier, the spring directly effecting the impacts.

The invention will be more fully explained in connection with the accompanying drawing in which Fig. 1 is a side view, with a casing cover removed, of the preferred form of my invention as embraced in 30 an impacting tool; Fig. 2 is a sectional view on line 2-2 of Fig. 1; Fig. 3 is a sectional view on line 3-3 of Fig. 1 with parts shown in full; and Fig. 4 is a view somewhat similar to Fig. 1 but showing a lesser portion, 35 the carrier and plungers being shown withdrawn from the abutment, the carrier being also shown in section.

The operating shaft 1 may be driven by any suitable means. In the drawings I have 40 illustrated an electric motor 2 brought into driving relation with this shaft through the intermediation of a spur pinion 3 upon the motor shaft and a spur gear 4 upon the operating shaft. The operating shaft may 45 function through any suitable means such as a spur pinion 5 which is preferably screwed

upon the shaft 1, a shoulder 6 upon the shaft limiting the extent to which pinion 5 may be screwed upon the shaft, this shoulder 55 cooperating with the adjacent face of the pinion to force the pinion and shaft to turn together upon continuation of the effort to screw the pinion further upon the shaft as will more fully appear, when opposite turning effort is applied to the pinion it will be 60 unscrewed a short distance from the shoulder to permit the pinion 5 to be arrested and subsequently turned faster than and in the direction of the shaft. The pinion is thus 65 in lost motion connection with the shaft.

The annular carrier 7 has a hub portion 7' by which this carrier is journaled upon the shaft 1 to be capable of turning in the course of operation both with respect to and in the direction of this shaft and the pinion 5 70 threaded upon the shaft. The plunger mechanism is shown as being employed in duplicate, though the invention is not to be thus limited. Each of the two plungers 8 and 9 is in the form of a rack in mesh with opposite sides of the common pinion 5. These 75 racks are movable upon and travel bodily with the carrier. Springs 10, 11 press upon the inner ends of the racks and serve, when free to act, to place the racks in their outer positions defined by suitable stopping means, such as the casing.

An abutment 12 is positioned within the circle of rotation of the outer ends of the racks when these racks are in their outer positions, whereby the 80 sides of the racks successively strike the abutment as the carrier is given intermittent turning movements that are rapid in the direction of the shaft and pinion. The invention is illustrated as being embodied in an 85 impacting tool in which the abutment is the butt or striking end of a drill 13 which passes through a casing 14 that houses the carrier and other parts, to project into the interior of the casing. The drill has a 90 shoulder formation 15 to limit the extent to which the abutment will enter the casing and define the functioning position of the abutment. The motor 2 and the gearing 3, 4 may 95 be carried by the casing upon its exterior. For convenience the casing is formed with an 100 extension 16 constituting a handle for the

device if it is to be of portable and manipulatable form.

Operation.—The shaft 1 is driven at a substantially constant speed by the motor 5 through the intermediation of the gearing 3, 4, and in a direction to screw the pinion 5 thereon against the shoulder 6 to enable the shaft and pinion to turn as a unit when required. Assuming the device to be in the 10 stage of operation illustrated, the pinion 5, coupled at 6 with the shaft draws the now non-rotating racks or plungers 8, 9 inwardly against the force of the springs 10, 11 until the rack 9 escapes engagement with the abutment, whereupon the springs distend and force the racks rapidly outward to points limited by the stopping means, in this instance the casing 14. The racks initially 15 travel upon and partially turn about the pinion 5 in the direction of the shaft at an increased or higher turning speed, as a consequence of the spring effected rotation of the carrier. When the racks are brought to their outer positions they acquire locking 20 engagement with the pinion 5, effected in any suitable way, as by engagement of the outer ends of the rack with the casing to arrest its rotation by the shaft, the speed of rotation of the pinion being consequently increased to screw it out of engagement with 25 shoulder 6. The pinion carrier and racks are thereafter turned at the higher or increased speed as a rigid unit in the direction of the shaft due to the momentum acquired 30 from the action of the springs until the side of the rack 8 at the outer end thereof strikes the abutment 12 with the momentive force, a first effect being to enable the shaft 1 to turn the pinion 5 into holding engagement 35 with the shoulder 6 whereupon the rack 8 is operated upon and operates as described in the case of rack 9.

Changes may be made without departing from my invention.

Having thus described my invention, I claim:—

1. The combination with an operating shaft; of a pinion screwed upon the shaft and free to turn thereon; a rotatable carrier 50 free to turn with respect to both shaft and pinion; a rack bodily movable upon and traveling with the carrier and in mesh with said pinion; a spring for placing the rack in an outer position; and an abutment with 55 which a side of the rack is brought into escaping engagement when the rack is in its outer position and cooperating with the pinion to effect inward abutment escaping movement of the rack against the force of the spring, said rack initially traveling upon the pinion and subsequently cooperating 60 with the carrier to screw the pinion in one direction upon the shaft when the rack is moved outwardly upon escaping the abutment, the turning shaft screwing the pinion thereon reversely when the rack engages the 65 abutment, there being holding formations upon the shaft and pinion that are engaged in this latter screwing movement of the pinion to enable the pinion to cooperate with the abutment to withdraw the rack 70 from engagement with the abutment against the force of the spring.

pinion thereon reversely when the rack engages the abutment, there being holding formations upon the shaft and pinion that are engaged in this latter screwing movement of the pinion to enable the pinion to cooperate with the abutment to withdraw the rack from engagement with the abutment against the force of the spring.

2. The combination with an operating shaft; of a pinion; a coupling between the 75 pinion and shaft enabling the shaft to turn the pinion and permitting the pinion to turn at a higher speed to break the coupling; a rotatable carrier free to turn with respect to both shaft and pinion; a rack bodily movable upon and traveling with the carrier and in mesh with said pinion; a spring for placing the rack in an outer position; and an abutment with which a side of the rack is brought into escaping engagement when the 80 rack is in its outer position and cooperating with the pinion to effect inward abutment escaping movement of the rack against the force of the spring, the rack when the spring is pressed outwardly upon escaping engagement with the abutment cooperating with the carrier to rotate the pinion at the higher speed to permit the rack to be thrust outwardly before the abutment is again reached by the rack.

3. The combination with an operating shaft; of a pinion screwed upon the shaft and free to turn thereon; a rotatable carrier free to turn with respect to both shaft and pinion; a rack bodily movable upon and traveling with the carrier and in mesh with said pinion; means for placing the rack in an outer position and increasing the speed of the carrier, and an abutment with which a side of the rack is brought into escaping engagement when the rack is in its outer position and cooperating with the pinion to effect inward abutment escaping movement of the rack, said rack initially traveling upon the pinion and subsequently cooperating with the carrier to screw the pinion in one direction upon the shaft when the rack is moved outwardly upon escaping the abutment, the turning shaft screwing the pinion thereon reversely when the rack engages the 115 abutment, there being holding formations upon the shaft and pinion that are engaged in this latter screwing movement of the pinion to enable the pinion to cooperate with the abutment to withdraw the rack 120 from engagement with the abutment against the force of the spring.

4. The combination with an operating shaft; of a pinion; a coupling between the pinion and shaft enabling the shaft to turn 125 the pinion and permitting the pinion to turn at a higher speed to break the coupling; a rotatable carrier free to turn with respect to both shaft and pinion; a rack bodily movable upon and traveling with the car- 130

rier and in mesh with said pinion; means for placing the rack in an outer position and increasing the speed of the carrier; and an abutment with which a side of the rack is brought into escaping engagement when the rack is in its outer position and cooperating with the pinion to effect inward abutment escaping movement of the rack, the rack when moved outwardly upon escaping engagement with the abutment cooperating with the carrier to rotate the pinion at the higher speed to permit the rack to be thrust outwardly before the abutment is again reached by the rack.

5. The combination with a rotatable carrier; of a rack bodily movable upon and traveling with the carrier; a driving pinion in mesh with the rack; means for driving the pinion and in lost connection therewith; a spring for placing the rack in an outer position; and an abutment with which a side of the rack is brought into escaping engagement when the rack is in its outer position and cooperating with the driving pinion to effect inward abutment escaping movement of the rack against the force of the spring, said rack initially traveling upon the pinion and subsequently cooperating with the carrier to turn the pinion loosely when the rack is spring pressed outwardly upon escaping the abutment in again moving the rack toward the abutment.

6. The combination with a rotatable carrier; of a rack bodily movable upon and traveling with the carrier; a driving pinion in mesh with the rack; means for driving the pinion and in lost motion connection therewith; means for placing the rack in an outer position and increasing the speed of the carrier; and an abutment with which a side of the rack is brought into escaping engagement when the rack is in its outer position and cooperating with the driving pinion to effect inward abutment escaping movement of the rack, said rack initially traveling upon the pinion and subsequently cooperating with the carrier to turn the pinion when the rack is moved outwardly upon escaping the abutment in again moving the rack toward the abutment.

7. The combination with a rotatable carrier; of a rack bodily movable upon and traveling with the carrier; a driving pinion in mesh with the rack; means for driving the pinion and in lost motion connection therewith; a spring for placing the rack in an outer position; and an abutment with which a side of the rack is brought into escaping engagement when the rack is in its outer position and cooperating with the driving pinion to effect inward abutment escaping movement of the rack against the force of the spring, said rack and pinion cooperating to turn the carrier to again move the rack toward the abutment.

8. The combination with a rotatable carrier; of a rack bodily movable upon and traveling with the carrier; a driving pinion in mesh with the rack; means for driving the pinion and in lost motion connection therewith; means for placing the rack in an outer position and increasing the speed of the carrier; and an abutment with which a side of the rack is brought into escaping engagement when the rack is in its outer position and cooperating with the driving pinion to effect inward abutment escaping movement of the rack, said rack and pinion cooperating to turn the carrier to again move the rack toward the abutment.

9. The combination with a rotatable carrier; of a rack bodily movable upon and traveling with the carrier; a driving pinion in mesh with the rack; means for driving the pinion and in lost motion connection therewith; a spring for placing the rack in an abutment engaging position; and an abutment with which the rack is brought into escaping engagement when the rack is in its abutment engaging position and cooperating with the driving pinion to effect abutment escaping movement of the rack against the force of the spring, said rack initially traveling upon the pinion and subsequently cooperating with the carrier to turn the pinion when the rack is spring pressed toward abutment engaging position upon escaping the abutment in again moving the rack toward the abutment.

10. The combination with a rotatable carrier; of a rack bodily movable upon and traveling with the carrier; a driving pinion in mesh with the rack; means for driving the pinion and in lost motion connection therewith; means for placing the rack in an abutment engaging position and increasing the speed of the carrier; and an abutment with which the rack is brought into escaping engagement when the rack is in its abutment engaging position and cooperating with the driving pinion to effect abutment escaping movement of the rack, said rack initially traveling upon the pinion and subsequently cooperating with the carrier to turn the pinion when the rack is moved to abutment engaging position upon escaping the abutment in again moving the rack toward the abutment.

11. The combination with a rotatable carrier; of a rack bodily movable upon and traveling with the carrier; and driving pinion in mesh with the rack; means for driving the pinion and in lost motion connection therewith; a spring for placing the rack in an abutment engaging position; and an abutment with which the rack is brought into escaping engagement when the rack is in its abutment engaging position and cooperating with the driving pinion to effect abutment escaping movement of the rack

- against the force of the spring, said rack and pinion cooperating to turn the carrier to again move the rack toward the abutment.
- 5 12. The combination with a rotatable carrier; of a rack bodily movable upon and traveling with the carrier; a driving pinion in mesh with the rack; means for driving the pinion and in lost motion connection therewith; means for placing the rack in an abutment engaging position and increasing the speed of the carrier; and an abutment with which the rack is brought into escaping engagement when the rack is in its 10 abutment engaging position and cooperating with the driving pinion to effect abutment escaping movement of the rack, said rack and pinion cooperating to turn the carrier to again move the rack toward the abutment.
- 15 13. The combination with a rotatable carrier; of a plunger carried thereby; a spring for moving the plunger to one position; an abutment positioned to be engaged by a side of the plunger when in this position; mechanism, supplied in addition to the abutment and in actuating relation to the plunger, cooperating with the abutment for effecting the movement of the plunger to an alternative position against the force of the spring 20 when the plunger engages the abutment and with the plunger and spring for effecting rapid movement of the carrier in a direction to carry the plunger toward the abutment; and means for driving said mechanism and in lost motion connection therewith.
- 25 14. The combination with a rotatable carrier; of a plunger carried thereby; means for moving the plunger to one position; an abutment positioned to be engaged by a side of the plunger when in this position; mechanism for effecting the movement of the plunger to an alternative position when the plunger engages the abutment and for effecting rapid movement of the carrier in a 30 direction to carry the plunger toward the abutment; and means for driving said mechanism and in lost motion connection therewith.
- 35 15. The combination with a rotatable carrier; of a plunger carried thereby; a spring for moving the plunger to one position; an abutment positioned to be engaged by the plunger when in this position; mechanism, supplied in addition to the abutment and in actuating relation to the plunger, cooperating with the abutment for effecting the movement of the plunger to an alternative position against the force of the spring when the plunger engages the abutment, said spring serving to effect rapid movement of the carrier in a direction to bring the plunger toward the abutment; and means for driving said mechanism and in lost motion connection therewith.
- 40 16. The combination with a rotatable carrier; of a plunger carried thereby; a spring device, when free to function, to move the plunger to one position; an abutment positioned to be engaged by a side of the plunger when in this position; mechanism, supplied in addition to the abutment and in actuating relation to the plunger, for effecting the movement of the plunger to an alternative position against the force of the spring when the plunger engages the abutment, said spring serving to effect rapid movement of the carrier in a direction to bring the plunger toward the abutment; and means for driving said mechanism and in lost motion connection therewith.
- 45 17. The combination with a rotatable carrier; of a plunger carried thereby; a spring for moving the plunger to one position; an abutment positioned to be engaged by a side of the plunger when in this position; mechanism, supplied in addition to the abutment and in actuating relation to the plunger, cooperating with the abutment for effecting the movement of the plunger to an alternative position against the force of the spring when the plunger engages the abutment, said spring serving to effect rapid movement of the carrier in a direction to carry the plunger toward the abutment; and means for driving said mechanism and in lost motion connection therewith.
- 50 18. The combination with a rotatable carrier; of a plunger carried thereby; a spring for moving the plunger to one position; an abutment positioned to be engaged by the plunger when in this position; mechanism, supplied in addition to the abutment and in actuating relation to the plunger, cooperating with the abutment for effecting the movement of the plunger to an alternative position against the force of the spring when the plunger engages the abutment, said spring serving to effect rapid movement of the carrier in a direction to bring the plunger toward the abutment; and means for driving said mechanism and in lost motion connection therewith.
- 55 19. The combination with a rotatable carrier; of a plunger carried thereby; a spring device, when free to function, to move the plunger to one position; an abutment positioned to be engaged by a side of the plunger when in this position; mechanism, supplied in addition to the abutment and in actuating relation to the plunger, for effecting the movement of the plunger to an alternative position against the force of the spring when the plunger engages the abutment, said spring serving to effect rapid movement of the carrier in a direction to bring the plunger toward the abutment; and means for driving said mechanism and in lost motion connection therewith.
- 60 20. The combination with a rotatable carrier; of a plunger carried thereby; a spring device, when free to function, to move the plunger to one position; an abutment positioned to be engaged by a side of the plunger when in this position; mechanism, supplied in addition to the abutment and in actuating relation to the plunger, for effecting the movement of the plunger to an alternative position against the force of the spring when the plunger engages the abutment, said spring serving to effect rapid movement of the carrier in a direction to carry the plunger toward the abutment; and means for driving said mechanism and in lost motion connection therewith.
- 65 21. The combination with a rotatable car-

tioned to be engaged by the plunger when in this position; mechanism, supplied in addition to the abutment and in actuating relation to the plunger, for effecting the movement of the plunger to an alternative position against the force of the spring when the plunger engages the abutment, said spring serving to effect rapid movement of

the carrier in a direction to bring the plunger toward the abutment; and means for driving said mechanism and in lost motion connection therewith.

In witness whereof, I hereunto subscribe my name.

JAMES LAROCCA.
